UNITED STATES PATENT OFFICE.

THOMAS R. KENNEDY AND EDWARD J. KING, OF ROCHESTER, NEW YORK, ASSIGNORS TO THE COOPERATIVE FOUNDRY COMPANY, OF SAME PLACE.

DESIGN FOR A HEATING-STOVE.

SPECIFICATION forming part of Design No. 29,393, dated September 20, 1898.

Application filed June 11, 1898. Serial No. 683,235. Term of patent 7 years.

To all whom it may concern:

Be it known that we, THOMAS R. KENNEDY and EDWARD J. KING, of Rochester, in the county of Monroe and State of New York, have invented and produced a new and original Design for Heating-Stoves, of which the following is a specification, reference being had to the accompanying drawings, forming a part thereof.

10 In the drawings, Figure 1 is a perspective view of a stove showing our design; Fig. 2, a plan view of the upper portion.

Similar reference letters and numerals in the figures indicate similar parts.

15 The leading features of our design consist of the shape and surface ornamentation of the stove as a whole and also of the shape and ornamentation of the separate sections thereof, as hereinafter described, and particularly of the shape or configuration of the top section E.

The base A of the stove is rounded outward and downward, its lower edge being indented, as shown, and its surface is covered 25 with the scroll and leaf ornamentation 1 in low relief, and at the corners are arranged the curved legs 2. Just above the base is the rounded band B, slightly smaller than the base and having the scroll-ornaments 3 at the corners and on the sides the repeated 30 ornamental design characterized by the vertical ribs 4, as shown.

The ash-pit section C is rounded outward slightly and then inward at the lower portion 35 where it meets the band B and at the corners is curved inward and provided with the ornamentation 5 in low relief and at the upper portion is provided with the rounded ornamental flange 6.

40 7 indicates the front ash-pit door, having the damper-openings 8 and provided with the curved depending apron 9, covered with the scroll and leaf ornamentation shown, and at the sides of the ash-pit are the side rails 10, 45 of graceful configuration and covered with the scroll and leaf ornamentation in low relief.

50 D indicates the body of the stove, arranged upon the ash-pit section and which is approximately annular in cross-section and divided by the ornamental zone or band 11 into two

parts, the upper part having the double ornamental mica doors 12 at the front and the single doors 13 at the side, and the lower part having the double ornamental mica 55 doors 14 at the front and the single doors 15 at the sides, the pillars or curved brackets 16 being arranged between the front and side doors, as shown.

E indicates the top section of the stove, recessed at the lower portion of the front and sides over the front and side doors in the body D for the reception of the ornamental mica-frames 17, having the rounded and ornamented upper sides, as shown. The shape 60 of this top section E is clearly shown in the drawings, being formed of a succession of graceful curved surfaces, and substantially the whole surface is covered with ornamental scrollwork in low relief.

65 F indicates the dome or cover on the top section E, having the band 18 at the lower edge, the upper portion of said dome being provided with the scroll ornamentation 19, as shown, and upon this cover is an ornament 70 or statuette 20, representing a knight on horseback.

We claim as our invention—

1. The design for a stove substantially as herein shown and described. 80

2. In a design for a stove, the design for the base, substantially as shown and described.

3. In a design for a stove, the design for the ash-pit door, substantially as shown and described. 85

4. In a design for a stove, the design for the side rail 10, substantially as shown and described.

5. In a design for a stove, the design for the stove-body D, substantially as shown and described. 90

6. In a design for a stove, the design for the top section E, substantially as shown and described.

7. In a design for a stove, the design for the cover F, substantially as shown and described. 95

THOMAS R. KENNEDY.
EDWARD J. KING.
